UNITED STATES PATENT OFFICE.

WALTER S. GRAY, OF CHICAGO, ILLINOIS, ASSIGNOR TO GOODMAN MANUFACTURING COMPANY, OF CHICAGO, ILLINOIS, A CORPORATION OF ILLINOIS.

LOCOMOTIVE.

Application filed July 20, 1922. Serial No. 576,254.

To all whom it may concern:

Be it known that I, WALTER S. GRAY, a citizen of the United States, residing at Chicago, in the county of Cook and State of Illinois, have invented an Improvement in Locomotives, of which the following is a specification.

This invention relates to improvements in locomotives and has for its principal object to provide an improved geared driving connection between the driving motor and a spring suspended axle wherein flexibility of movement of the latter is afforded relative to the motor and the locomotive frame.

My invention is particularly advantageous in the construction of locomotives of the single motor type, in which two or more spring suspended axles have driving connection with the motor. By the adoption of my improved construction, relative flexibility is afforded between the driving axles to permit, within reasonable limits, vertical and rocking movements thereof relative to each other.

My invention may best be understood by reference to the accompanying drawings in which—

Figure 1 is a view in elevation of a single motor locomotive constructed in accordance with my invention.

Fig. 2 is an enlarged transverse cross-section taken on line 2—2 of Fig. 1.

Fig. 3 is a detail taken on line 3—3 of Fig. 2, but drawn to a larger scale.

In Fig. 1 my invention is shown as applied to a locomotive having a frame 1, a motor 2 and two axles 3, 3, provided with supporting wheels 4, 4. Each of the axles are connected at opposite ends to the locomotive frame 1 by journal boxes 5, 5, moving in vertically disposed guides 6, 6, formed in the opposite sides of the frame in the usual manner. Supporting springs 7, 7, are interposed between the frame and the tops of the journal boxes 5, 5.

Driving connection between the motor 2 mounted on the frame 1 as aforesaid and each of the axles 3, 3, comprises suitable gearing rotatably mounted on the frame, as for instance an armature pinion 10 and a gear 11 interposed between and meshed with driving gears 12, 12, associated with each of the axles. These driving gears are each keyed on a hollow driving member 13 journaled in a bearing 14 carried by the frame 1.

Each axle 3 extends longitudinally through one of said driving members 13, and when said axle is in its normal position, it is substantially concentric with its respective driving member, as shown in Fig. 2. Suitable clearance is provided between the axle 3 and its driving member 13 to allow the desired amount of vertical movement of the axle and supporting wheel respective to the driving member and frame. Driving connection between each driving member 13 and its axle 3 is afforded by means of a flexible coupling. In the embodiment illustrated, this flexible coupling is of the "Oldham" type, comprising a perforated plate 15 surrounding the axle 3 and provided with oppositely disposed splines 16, 16, adapted to engage in grooves 17, 17, formed in the lateral face of collar 18 formed integral with the driving member 13. A pair of splines 19, 19, are carried on the opposite side of the plate 15 substantially at right angles to the first mentioned splines 16, 16, and are engaged in grooves 20, 20, formed in the face of a collar 21 keyed on the axle 3. The plate 15 is provided with an elongated aperture 23 through which the axle 3 extends so as to permit lateral movement of said plate respective to said axle in a direction parallel with splines 19, 19, as shown in Fig. 3. The arrangement is such that the plate 15 is permitted to "float" or accommodate itself and afford driving connection between collars 18 and 21, either when they are in normal alignment or when out of alignment due to vertical displacement of the axle. Horizontal clearance between the plate 15 and the co-acting collars 18 and 21 is provided to permit limited tilting or rocking of the axle 3 with respect to the driving member 13 and frame. Furthermore, the outer ends of the splines 16, 16, and 19, 19, are also formed convex, as indicated at 24 to allow relative freedom of movement of the parts.

It will be observed that the coupling is positioned at the approximate center of the axle. This arrangement is preferred as it permits the maximum displacement of opposite ends of the axle when the latter tilts or rocks in a vertical plane. It will be understood, however, that the coupling may be positioned adjacent one end of the axle or the other, if desired, without materially affecting the function of the device.

The purpose and operation of the mecha-

nism is probably sufficiently understood from the above description in which it will be seen that the two axles have a geared driving connection with the motor mounted on the locomotive frame, but each of the axles is afforded vertical and rocking movement independently of each other and of the frame.

Although it is manifest that substantial relative freedom of movement between the two axles may be afforded if only one of said axles is mounted and driven through the mechanism above described and the other is mounted rigid with respect to the motor and frame, yet it is preferable in order to afford maximum relative flexibility and spring suspension for both axles to provide both axles with flexible, geared couplings as described. It is furthermore obvious that equivalent forms of flexible couplings can be substituted for the "Oldham" type of coupling, as for instance, a coupling of the link type might be utilized without departing from the spirit and scope

of my invention. I do not, therefore, wish to be understood as limiting myself to the specific construction illustrated herein excepting as specifically limited in the appended claim.

I claim as my invention:

In a locomotive, a frame, a motor mounted on said frame, two laterally spaced axles, spring suspension means interposed between said axles and said frame, a pair of hollow driving members rotatably mounted on said frame and having operative connection with said motor, each of said driving members extending longitudinally about one of said axles but spaced therefrom to permit relative movement thereof in a vertical plane, and a flexible coupling device operatively connecting each of said driving members with its respective axle at the approximate center of the latter.

Signed at Chicago, in the county of Cook, and State of Illinois, this seventh day of June, 1922.

WALTER S. GRAY.
